Frederick P. Manning

UNITED STATES PATENT OFFICE.

FREDERICK P. MANNING, OF BATAVIA, ILLINOIS.

METAL TANK.

SPECIFICATION forming part of Letters Patent No. 664,421, dated December 25, 1900.

Application filed March 8, 1900. Serial No. 7,836. (No model.)

To all whom it may concern:

Be it known that I, FREDERICK P. MANNING, a citizen of the United States, residing at Batavia, in the county of Kane and State of Illinois, have invented a new and useful Tank, of which the following is a specification.

My invention relates to improvements in metal tanks; and the objects of my improvements are, first, to provide a metal tank having the greatest durability; second, to provide a metal tank requiring the least amount of work in its construction; third, to provide a tank having no seam running around bottom, and, fourth, to provide a metal tank without seams in its corners. I attain these objects by constructing as illustrated in the accompanying drawings, in which—

Figure 1 is a detailed view in perspective of metal tank as constructed. Fig. 2 is a pattern showing manner in which metal sheets are cut and made up to form tank. Fig. 3 is a vertical section of lock-seam.

Similar letters refer to similar parts throughout the several views.

The sheets of metal A, the end pieces B, the angle-irons C, the braces C', and rivets U constitute the several parts of tank.

In constructing tank I use one or more sheets of metal lock-seamed together until I have required length of tank, as shown by seams O, each seam being hammered down and grooved, as shown by Fig. 3. I prefer to have the metal sheets A equal in length to both sides and bottom of tank E, Fig. 1; but when necessary the sheets A can be lengthened by lock-seaming two sheets together, as shown at O', thus making the body of tank. The ends B having the folds S are lock-seamed onto the body of tank E, as shown in Fig. 2. The holes N in ends B show where riveted after being formed up, as at U, Fig. 1.

To form up sheets or body E in Fig. 2, bend

up the sides and ends at dotted lines M to a right angle with the bottom lock-folds S in ends B in folds F in body E, rivet at N in ends B, and solder seams O and O' and rivets U, as in Fig. 1.

The angle-irons C are riveted around top and bottom of tank E and also at each corner of tank E, as shown in Fig. 1. The braces C' are riveted across top of tank E to angle-irons C to prevent sides of tank E from spreading when filled with liquid.

I am aware that prior to my invention metal tanks have been made in combination with angle-irons. I therefore do not claim such a combination broadly; but

What I do claim as my invention, and desire to secure by Letters Patent, is—

1. The combination in a metal tank of the metal sheets A A A A, the lock-seams O O O O joining the metal sheets A A A A, the ends B B lock-seamed onto the sheets A A A A and having the folds S S S S and the rivets U U U U, the angle-iron C C C C C C C C, the braces C' C' all substantially as described and set forth.

2. The combination in a metal tank of the angle-iron C C C C C C C C, the braces C' C' the ends B B having the folds S S S S and the rivets U U U U, the lock-seam O' running lengthwise of tank E and joining two sheets of metal of sufficient length and breadth to form both sides and bottom of tank E, substantially as set forth and described.

3. In a metal tank the combination of the metal sheets A A A A, the seams O O O O and O', the ends B B, the angle-iron C C C C C C C C, the braces C' C', constructed as set forth and described.

FREDERICK P. MANNING.
